KONRAD VICTOR VON MEYENBURG, OF BASEL, SWITZERLAND, ASSIGNOR TO THE FIRM
OF MOTOCULTURE LIMITED, OF BASEL, SWITZERLAND.

TILLING-MACHINE.

1,171,010.

Specification of Letters Patent.

Patented Feb. 8, 1916.

Application filed March 12, 1913. Serial No. 753,789.

To all whom it may concern:

Be it known that I, KONRAD VICTOR VON MEYENBURG, a citizen of the Swiss Republic, and resident of Basel, Switzerland, have 5 invented new and useful Improvements in Tilling-Machines, of which the following is a full, clear, and exact specification.

My invention relates to a practicable tilling machine having a motor driven rotary 10 tool carrier arranged behind the running or drive wheels of the carriage or machine, which machine is so constructed, that not only the running speed of the machine, but also its working width can easily be varied, 15 and this without any troublesome changes being necessary on the carriage frame or in the drive mechanism of the rotary tool carrier. To this end, the rotary tool carrier or its shaft, instead of being supported, 20 as is usual, by its terminal parts, is supported only in its middle part by means of a hollow bracket piece forming part of a rigid structure constituting at the same time the carriage frame and an inclosing and holding box for the motor, the driving axle of 25 the wheels and the transmission gear, part of which is located within said hollow bracket piece supporting the rotary tool carrier, said bracket piece serving thus at 30 the same time as a guard therefor.

The improved machine is particularly designed for the middle class of peasants or farmers and allows of great variation of the surface work efficiency by varying not only 35 the traveling speed, but also the effective working width of the machine, which may be done relatively easily and rapidly.

The accompanying drawing represents the preferred form of the improved tilling 40 machine.

Figure 1 is a side view of the machine with a rear sustaining device for the rotary tool carrier and a following sowing device. Fig. 2 is a vertical section along the line 45 A—B of Fig. 1. Fig. 3 is a horizontal section along the line C—D of Fig. 1.

Between the running wheels *a* of the machine is arranged the carriage-frame *b* consisting of a preferably closed box or receptacle and inclosing in the known manner a combustion motor *c* together with the gears driven thereby and driving in their turn the running wheels *a* and the rotary tool carrier *d*. This gear mechanism com-

prises in the first line the shaft *e* driven by 55 the motor and which, by means of a worm gear device *f* and a speed change gear mechanism (not represented), drives on the one hand the running wheels *a* of the machine, while on the other hand, by means of conical toothed wheels *g*, it rotates an intermediate shaft *h* actuating by means of a chain gear the rotary tool carrier *d*. The rotary tool carrier *d* consists of a revoluble shaft *k* with scraping tools arranged thereon, which 60 shaft is supported in its middle part by a central bracket piece *m* constituting a rear part of the carriage frame box *b*, so that it protrudes laterally with its halves which 65 carry the tools. The aforesaid bracket piece *m* is hollow and between its side cheeks there is fixed upon the shaft *k* a chain wheel *o* connected by a chain *n*, inclosed in said 70 hollow bracket piece *m* to another chain wheel *p* mounted on the intermediate 75 shaft *h*.

The bracket piece *m* is provided with an upward and laterally projecting reinforcing rib *q* carrying at its rear end the center of a vertically adjustable hollow transverse beam *r* serving, if desired, to support a tool carrier covering roof. The transverse beam *r* supports behind the rotary tool carrier one or more pressure or staying rollers *s* which may be adjustable in the direction of 80 the height; moreover, it carries a sowing device *t* which may also be adjustable in the vertical direction, and finally a rake *u* arranged in front of the sustaining rollers *s*. The central fastening of the transverse beam *r* allows of the easy changing of position, exchanging and extending of said 85 roof, roller device, sowing device and rake in the like manner as and according to the above said changes of the main rotary tool. 90

A depending spur *v* on the bracket piece *m* is designed to crush or throw down the earth tongue which during the operation of the rotary tool carrier remains below the middle part thereof (where, obviously no 100 tools are arranged).

On the front end of the frame box *b* or, if desired, on the transverse beam *r* are fastened two handle bars *w* by means of which the motor driven machine may be manually 105 governed or directed by a governor going ahead or on the side of the machine.

Advantageously, the running wheels *a*

may be adjustable upon their axle so that, if necessary, their gage can be adjusted in conformity with crops growing in rows.

What I claim is:

- 5 1. In tilling machines, the combination of running wheels, a rotary tool carrier with a shaft arranged behind said running wheels, a driving motor, a gear mechanism between said motor and the shaft of said rotary tool carrier, a further gear mechanism between said motor and said running wheels, a rigid structure constituting at the same time the carriage frame and a holding and inclosing box for the driving motor and
- 10 15 said gear mechanisms and comprising a rear central hollow bracket piece for supporting the rotary tool carrier shaft in its middle part and inclosing part of the first named gear mechanism.
- 20 2. In tilling machines, the combination of running wheels, a rotary tool carrier with a shaft arranged behind said running wheels, a driving motor, a gear mechanism

between said motor and the shaft of said rotary tool carrier, a further gear mechanism between said motor and the running wheels, a carriage frame box for the motor and said gear mechanisms, having a rear part formed by a bracket piece for supporting the rotary tool carrier shaft in its middle part so as to leave sidewardly free both its halves, with the tools, said bracket piece being hollow and inclosing part of the first named gear mechanism, and a transverse beam centrally supported on said bracket piece to the rear of said rotary tool carrier and adapted to carry auxiliary implements on its laterally extending portions.

In witness whereof I have hereunto signed my name this 18th day of February, 1913, in the presence of two subscribing witnesses.

KONRAD VICTOR VON MEYENBURG.
